(57) **CLAIM**

The ornamental design for a clinical analyzer, as shown and described.

DESCRIPTION

This application contains subject matter related to the following co-pending U.S. design patent applications:

Application Ser. No. 29/627,767, filed herewith and entitled “Clinical Analyzer”;

Application Ser. No. 29/627,777, filed herewith and entitled “Clinical Analyzer”;

Application Ser. No. 29/627,780, filed herewith and entitled “Clinical Analyzer”;

Application Ser. No. 29/627,764, filed herewith and entitled “Clinical Analyzer”;

Application Ser. No. 29/627,774, filed herewith and entitled “Clinical Analyzer with Graphical User Interface”; and

Application Ser. No. 29/627,781, filed herewith and entitled “Clinical Analyzer with Graphical User Interface”.

FIG. 1 is a front, top and right side perspective view of a clinical analyzer according to the design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a rear elevational view thereof;

FIG. 8 is enlarged cross-sectional view taken in the direction of line 8-8 of FIG. 2;

FIG. 9 is an enlarged cross-sectional view taken in the direction of line 9-9 of FIG. 2;

FIG. 10 is an enlarged cross-sectional view taken in the direction of line 10-10 of FIG. 2;

FIG. 11 is an enlarged cross-sectional view taken in the direction of line 11-11 of FIG. 2; and,

FIG. 12 is a front, top and right side perspective view thereof shown in an opened position.

The broken lines illustrate portions of the clinical analyzer that form no part of the claimed design.

1 Claim, 10 Drawing Sheets
